UNITED STATES PATENT OFFICE

ADOLPH MARCHAND, OF JACKSON HEIGHTS, NEW YORK, N. Y.

DESIGN FOR A MIRROR

Application filed March 30, 1931. Serial No. 39,298. Term of patent 7 years.

To all whom it may concern:

Be it known that I, ADOLPH MARCHAND, a citizen of the United States, residing at 231 81st Street, Jackson Heights, in the county of Queens, city and State of New York, have invented a new, original, and ornamental Design for Mirrors, of which the following is a specification, reference being had to the accompanying drawings, forming part thereof.

I claim:

The ornamental design for a mirror, as shown.

ADOLPH MARCHAND.
